PNEUMATIC SHEET FEEDING MECHANISM

Georg Spiess, Leipzig, Germany

Application April 13, 1950, Serial No. 155,574

7 Claims. (Cl. 271—47)

1

The present invention relates to a mechanism for the feeding of sheets of paper, cardboard, metal sheets etc. from a pile or web to printing, folding or other sheet operating machines whereby the sheets are fed, either singly one after the other or in an overlapping manner, in the direction of the front register to the operating machine. At the end of this feed mechanism i. e. at the transition to the operating machine there is a control mechanism provided for the testing of the feed of the sheet into the operating machine. If this control mechanism reacts, for instance in a case of a sheet not arriving or of any other disturbing reason, an automatic disengagement of the operating machine will result and at the same time the sheet feed mechanism will automatically be stopped entirely. The sheets, lying on the feed table, which has continually running carrying belts, rest therefore in the position which they occupy. At such an event, the so-called "stopper" the sheet lying at the front register stops, which caused the stoppage is removed and afterwards the sheet feed mechanism is actuated again. Jolts will occur at such reactuating of the sheet feed mechanism especially in fast running feeding machines and the sheet carrying belts will slip on their rollers. Accordingly the sheets lying on the carrying belts will shift and another "stopper" may be expected immediately. That is the reason why it is preferred in case of a "stopper" to remove from the feeding belt all sheets lying on it. This causes not only a longer loss of time and a considerable impairment of production capacity but also mostly results in the disadvantage that the sheets get dirty or damaged and become useless. This is especially disadvantageous in colour-printing work.

Separate devices with special handles to operate them are arranged on these mechanisms for putting the belt driving roller into operation again and for turning on the air current for the nozzles. In starting again, first of all the handle for the control of the air current to the nozzles has to be operated. Next the belt driving roller is actuated by another handle. This latter operation has to be made at an exactly determined moment, and this calls for very special attention by the operator, otherwise another "stopper" will immediately occur. In practice, therefore, all sheets will be taken off the feed even in these mechanisms, when a "stopper" occurs. The above mentioned disadvantages will however occur again.

It is an object of the present invention to provide a sheet feed mechanism for sheet operating

2

machines which eliminates the disadvantages described above.

According to the present invention the sheet feed mechanism is likewise constructed in such a way that only the belt driving roller is stopped and the air current for the nozzles is cut off when a "stopper" has occurred, but the operator has to manipulate one handle only for putting the sheet feed into operation again and does not have to watch any other movements, and in consequence to the hereby influenced means the feed of the sheets is made exactly registered to the front register stops of the operating machine as well as the taking off the next sheet of the pile by the nozzles.

According to the present invention this will be attained in such a way that all the means of the mechanism for the automatic stopping of the sheet carrying are positively connected to a shaft on which is a handle (cranked handle, hand-wheel or such like) the operating of which controls the air current for the nozzles as well as puts the belt driving roller of the sheet feed into operation again. Thereby the means, provided for the control of the air current to the nozzles and for putting the belt driving roller into operation again, come into force automatically at a determined time during the working rhythm of the mechanism for the exact registering of the feed of the sheets to the front register stops of the operating machine.

The sheets lying on the feed table are suitably held in position by special holding devices during the stopping of the sheet feed so that the sheets cannot be displaced when the sheet is taken off which caused the disturbance. There are also holding devices provided above the pile which press on the pile during the time in which the nozzles are working without air so that the top sheets of the pile cannot be displaced by the lost motion of the nozzles.

In the accompanying drawings the object of the invention is shown in one example of design, and it shows:

45 Fig. 1 the sheet feed mechanism in a side view.
Fig. 2 a view in direction of the arrow A of Fig. 1.

Fig. 3 the clutch coupling for connecting and disconnecting of the sheet carrying in connected position.

Fig. 4 the device for making the nozzles to take the sheets off the pile exactly in register, the said device being in the position it occupies after the sheet carrying has been put into operation again.

Fig. 5 the same device but in turned off position.

Figure 6 is a fragmentary elevational view of the control valves;

Figure 7 is a sectional view taken on line 7—7 of Fig. 6;

Figure 8 is a view similar to Fig. 7 showing the valve in a different position.

The sheets are taken off a pile 1, for instance, the said pile constructed in a known way so that it can be raised or lowered. The sheets are taken off also in a known way for instance by suction nozzles 2 which forward the taken off sheet to carrier nozzles 3. The sheets are then by means of the said carrier nozzles 3 forwarded to the driven belt roller 4 which acts in connection with timing rollers. The sheets come from here either in an overlapping manner (as it is shown in Fig. 1) or singly one after the other to the front register stops 7 of a sheet operating machine 8 for instance a printing machine, by way of a feed, consisting of continuously moving conveyor belts 5, and passing a feed table 6. The speed of the conveyor belts is such as to guarantee that on each occasion when grippers on the pressure cylinder of the printing machine pass the front register stop 7 of the stacking table 13, a sheet, and only one sheet, is ready to be picked up. A control mechanism 9 is arranged near the front register stops 7, and serves the purpose of testing and controlling the feeding of the sheets to the operating machine. The control mechanism 9 is provided with feeler fingers suspended so that they can swing. In the drawing, Fig. 1, they are represented in the highest position. At approximately the same time as the front sheet 14 reaches the front register stop 7, the fingers sink against the table. Normally they contact one sheet. If when swinging downwards, the fingers should, however, fail to contact a sheet at the front register stop 7, or if the sheet at the stop 7 should have a piece torn out of it, the feeler fingers come into contact with the table. At the spot where the fingers 9 touch the table or an extension thereof, there is an insulated contact plate which is in circuit with one branch of a lead forming a circuit through electro-magnet 16. The other branch of this lead is attached to the finger or fingers 9. If, therefore, one of the feelers 9 comes into contact with the plate when the latter is not covered by a sheet, the circuit will be closed, with corresponding excitation of the electro-magnet 16. The control mechanism 9 will react in case of any irregularity. The effect of this reaction is:

The operating machine 8 will automatically be stopped, so will the sheet carrying devices 4, 5 and at the same time the air current to the nozzles 2, 3 will be cut off. The sheets 10 to 14 stay in the position they occupy and are pressed by the conveyor rollers 15 which work in connection with the conveyor belts 5, and the nozzles 2, 3 continue their working rhythm without air current and cannot take any sheets off the pile 1.

Electro-magnet 16 is arranged underneath the sheet feed. The said electro-magnet 16 has a tappet 17 which works against a releasable catch 18 locking a tie rod 19 when sheet feed is regular. The catch 18 is fitted in a bearing at one end at 100 so that it will turn. On its underside at 101 there is a point provided. Against this point 101 abuts a nose 102 fitted on one side. Due to the contact between the nose 102 and the point 101 on the catch 18, the bar 19 is prevented from yielding to the pull of the spring 20. If the electro-magnet 16 is excited by the effect of the sheet detector, the tappet 17 (core of the

electro-magnet) moves upwards (shown in Fig. 2). When making this movement, it takes the releasable catch 18 with it, against the end of which lies the free end of the tappet 17, thus drawing the projection 101 on the releasable catch 18 away from the nose on the tie-rod 19. As soon as the projection 101 is separated from the nose 102, the spring 20 comes into action moving the rod 19 to the right in the direction of the arrow x in Fig. 2. When the control mechanism 9 reacts the tappet 17 will be pressed against the catch 18 and the tie rod 19 will thereby become released. To the tie rod 19 on the one side is connected a cranked connecting rod 21 which acts on a lever 22, the said rod 22 being spring pressed. Part 22 consists of a tube housing a spiral spring. Both ends of this spring are supported by bolts passing through longitudinal slits in the tube. One of the bolts is connected to one arm of a crank lever 21 and the other bolt with one arm of the crank lever 23. The spring tension is so great that in most cases the movement of crank lever 21 is directly transmitted through the spring to the crank lever 23. If when lever 21 moves there is some hindrance to the movement of lever 23 (e. g. because the two halves of the clutch coupling 24 cannot immediately be brought into contact), a movement of lever 21 will first of all cause the spring in the tube to be compressed. The crank lever 21 can be displaced in the sense that lever 23 does not participate in the movement of lever 21. As soon as the obstruction against the free movement is removed, i. e. when both halves of the coupling 24, for instance, have come together in a manner enabling them to engage correctly, the tension in the spring takes effect and causes a subsequent movement of the lever 23. On the rod 22 is arranged a cranked lever 23 the short arm of which engages a two part clutch coupling 24. The clutch coupling 24 is mounted on a shaft 29 in such a way that the shiftable half rotates with the shaft and the other half is freely rotatably mounted on the shaft 29. A spur gear 30 is arranged on the movably connected half of the clutch coupling 24, the said spur gear 30 engaging a spur gear 31 and driving the shaft 34 by means of the spur gears 32, 33. The driving roller 4 is rigidly connected to the shaft 34 and drives the conveyor belts 5 of the sheet feed. To the tie rod 19 on the other side is connected a lever 25 rigidly fastened to a shaft 26 which has a worm gear 27 which engages a worm gear 28. The worm gear 28 is rigidly connected with a shaft 36 on which a revolving piston is arranged inside of an air valve box 37. Figures 6-8 show that the revolving piston is formed like a plug, i. e. the piston consists of a cylinder with bores for registering with each of the leads 38 and 39. The revolving piston can be so set that the bores come into register with the leads 38 and 39 so that air can pass through unhindered. If it is turned through 90°, the flow of air is stopped in the well-known manner.

The boring in the piston which registers with lead 39 has a branch lead running into it perpendicularly, thus forming a three-way valve at this point in the well-known manner. By designing the piston in this way, it is possible, when lead 39 is cut off—to connect the leads 48 and 49 to the suction pump. The revolving piston controls in a known way the valves for the compressed-air tube 38, which directs air horizontally against the topmost sheet of the pile 1 through

a nozzle (not shown) and for the suction-air tube 39.

The lever 25 is firmly attached to the shaft 26, to which is firmly keyed the diagonally cut gear 27. A movement of the tie rod 19 causes 5 the shaft 26 to be turned through the lever 25, thus also the worm gear 21, in mesh with worm wheel 28, which also turns. Vice versa, a movement of the hand crank 40 will again cause the cog wheel 28 to operate the gear 27, turning the shaft 26, so that the arm 25 fixed to the shaft 26 will displace the tie rod 19.

In case the tie rod 19 is automatically released by the control mechanism 9 then the clutch coupling 24 will become positively disengaged by 15 means of the lever system 21, 22, 23. In this way the spur gear 30 will be stopped and so will the belt driving roller 4. At the same time the worm gear pair 21, 28 will be positively actuated by the lever 25. Thereby the revolving piston will control the valves of the pressure and suction-air tubes 38, 39 so that the pressure air nozzle and the nozzles 2, 3 do not get any air. Accordingly the sheets 10 to 14, are stopped by 20 stoppage of the conveyor belts and the nozzles 2, 3 cannot take any more sheets off the pile 1.

If the sheet 14 having caused the "stopper" is now removed and the disturbance cleared away then the mechanism can be started again without further consideration and for this there is only one movement necessary according to the present invention. For this purpose a handle 40 is provided (the said handle being a cranked handle, a hand-wheel or such like) fixed on the shaft 36 with which all the means of the mechanism for stopping the sheet carrying are positively connected. By turning the said handle 40 in a counterclockwise direction (Fig. 1) which turning however is possible only at a certain moment (what will be described later on) the revolving piston will be rotated to normal position and in this way the pressure and suction-air currents of the air tubes 38, 39 will be turned on so that the nozzles 2, 3 are fed with air again. Moreover the lever 25 by means of the worm gears 27, 28 and thereby the tie rod 19 will be moved back so that by means of the lever system 21, 22, 23 the clutch coupling 24 becomes engaged again and by means of gear 30—34 the belt driving roller 4 is set in a turning motion. The clutch coupling 24 is constructed as a one tooth clutch coupling and the lever 22 is equipped with a spring. For the engagement of the tooth of the clutch coupling, which said tooth is on the shiftable half of the clutch coupling, there is provided a recess on the other half of the clutch coupling which is continuously turning with the shaft 29. This recess is synchronized to the rhythm of the mechanism for an exactly registered feed. After the sheet feed has been put into operation again by 45 means of the cranked handle 40 the spring of the lever 22 presses against the lever 23 until the short arm of the said lever 23 has securely engaged the tooth of the clutch coupling with the recess. This friction guarantees that the start is made at the right moment. At the back movement of the tie rod 19 the catch 18 has been engaged again with the bolt of the shaft.

In order also to guarantee that the nozzles 2, 3 take the next sheet off the pile 1 in right time and in such a way that the distance from the preceding sheet 10 is accurate or approximately accurate, an eccentric 41 is provided on the shaft 29 against which a roll 42 rolls up. The roll 42 is arranged on a double arm swinging lever 43, 75

which is spring-pressed. The arm 44 acts against a segment 45 arranged on the shaft 36. If the tie rod 19 has been released and the sheet carrying has thereby been stopped the shaft 36 and thereby the segment 45 will be turned by means of the gear 27, 28 and by this the swinging lever 43, 44 will be moved with its arm 44 over a gliding surface of the segment 45. The segment 45 can be turned again only when the arm 44 has left this gliding surface (see: position in Fig. 5 broken lines) and this is determined by the rotation of the eccentric 41. The eccentric 41 has an eccentric boss corresponding with such a position of the working rhythm of the nozzles 2, 3 determined by the shaft 29, in which the nozzles 2 set down on the pile 1 in order to take off the next sheet. The operator has only to press the cranked handle 40 without having to pay heed to any movements in order to put the sheet carrying into operation again. The segment 45 prevents a turning of the cranked handle 40 if the right position respectively the correct moment for starting the mechanism again has not yet arrived. The cranked handle 40 can only be moved when the arm 44 of the swinging lever 43, 44 which continues oscillating even during the stopping of the sheet carrying has left the gliding surface of the segment 45 (Fig. 5 broken lines) and then the segment 45 will move 20 into the position shown in Fig. 4. This moment of the control is determined by the eccentric 41. Movement of the cranked handle 40 will also positively actuate through the gears 27, 28 the engagement of the clutch coupling 24 for starting 25 the belt driving roller, and will effect turning of the shaft 36 and in turn the control of the air current for the nozzles 2, 3.

It is also desirable to hold the sheets lying on the feeder securely as it has been suggested 30 above. According to the present invention special holding devices 46, 47 can be provided for this purpose on the mechanism either underneath the feed way (as shown in Fig. 1) or above it. The holding devices 46, 47 are for instance devised as air controlled pistons arranged in an air tight box and being spring-pressed the said pistons acting from underneath against the back of the sheets 12, 13 i. e. sucking the sheets from underneath. For this purpose air tubes 48, 49 are provided connected with the piston 35 box and leading to the air valve box 37. If the sheet feed is stopped and the pressure- and suction-air currents are turned off in the manner described above then according to the present invention the suction tube 39 will be simultaneously connected with the tubes 48, 49 and thereby the pistons 46, 47 will be moved against the back of the sheets 12, 13. Upon placing the sheet feeder into operation again, the air current will be directed back to the nozzles 2, 3 thereby the air tubes 48, 49 will be turned off again from the air tube 39 and the pistons 46, 47 will release the sheets 12, 13.

According to the present invention there are 40 furthermore provided holding devices above the pile 1. These sheet holding devices are for instance devised as spring-pressed valve pistons 50 which can be connected with the suction tube 39. For this purpose an air tube 51 leading to the air valve box 37 is connected with the casting of the valve piston 50. When the pressure and suction-air currents have been turned off the suction-air tube 39 will simultaneously be connected with the tube 51 and thereby directed 45 to the valve piston 50 or to some more valve

pistons so that it moves against the pile 4 and presses on it. By starting the sheet feed again the air current will be directed back again to the nozzles 2, 3 the air tube 51 therefore is again turned off the suction-air tube 39 and the valve piston 50 is raised from the pile under the influence of its spring.

If the operator wants to stop the sheet carrying for some other reason there is yet another, mechanical stopping device provided for such cases which acts on the catch 18, consisting for instance of the lever rods 52, 53, 54 the angle lever 53 of which is with the catch 18 supported by a support 55 arranged on the wall of the mechanism. The lever 54 is provided with a handle, the catch 18 will be pressed upwards when the said lever handle is pulled, and the tie rod 19 will thereby become released. In order to put the mechanism into operation again the cranked handle 40 will also be operated in such a case.

The present invention provides finally a stopping device for such cases when only the sheets 10 to 14 lying on the feed table shall be fed to the operating machine 8 for instance to finish off the edition. In connection with the tubes 38, 39 for the pressure and suction-air currents there is for this purpose a casing 56 provided with a spring-pressed auxiliary piston 57. This said piston 57 is shiftably supported and will be operated by hand. By pressing against the piston 57 it will be moved and will close the suction-air current for the nozzles 2, 3. The piston 57 has to be pressed until the last sheet has been fed to the operating machine. Having done this the mechanism will be stopped altogether entirely.

What I claim as my invention and desire to secure by Letters Patent of the United States is:

1. A sheet feeder comprising an endless conveyor for transporting sheets to a machine to be fed, means provided with suction grips for lifting and transferring a top sheet from a pile to the conveyor, a main driving shaft, means for driving the conveyor from the driving shaft including a clutch, a conduit connected with said suction grips, a valve in said conduit, an actuator for engaging and disengaging said clutch, an actuator for said valve, means interconnecting the clutch and valve actuators, spring means urging the clutch to disengaged position and the valve to closed position, a locking device for retaining the clutch engaged and the valve open against the action of said spring, a sheet detector positioned at the end of said conveyor, means controlled by the sheet detector and operable for releasing the locking device, and a single manually operated control element connected to said actuators for engaging the clutch and opening said valve and resetting the locking device.

2. A sheet feeder comprising an endless conveyor for transporting sheets to a machine to be fed, means provided with suction grips for lifting and transferring a top sheet from a pile to the conveyor, a main driving shaft, means for driving the conveyor from the driving shaft including a clutch, a conduit connected with said suction grips, a valve in said conduit, an actuator for engaging and disengaging said clutch, an actuator for said valve, means interconnecting the clutch and valve actuators, spring means urging the clutch to disengaged position and the valve to closed position, a locking device for retaining the clutch engaged and the valve open

against the action of said spring, a sheet detector positioned at the end of said conveyor, means controlled by the sheet detector and operable for releasing the locking device, a single manually operated control element connected to said actuators for engaging the clutch and opening said valve and resetting the locking device, and means locking the manually operated control element during a given period of revolution of the main driving shaft, and a yieldable member in the means interconnecting the clutch and valve actuators.

3. A sheet feeder comprising an endless conveyor for transporting sheets to a machine to be fed, means provided with suction grips for lifting and transferring a top sheet from a pile to the conveyor, a main driving shaft, means for driving the conveyor from the driving shaft including a clutch, a conduit connected with said suction grips, a valve in said conduit, an actuator for engaging and disengaging said clutch, an actuator for said valve, means interconnecting the clutch and valve actuators, spring means urging the clutch to disengaged position and the valve to closed position, a locking device for retaining the clutch engaged and the valve open against the action of said spring, a conveyor table about which the conveyor extends, on and off feeler fingers carried by the table, movable contact plates fitted in the table opposite the feeler fingers, an electromagnet, a circuit for energizing said magnet including said fingers, plates and electromagnet means actuated by said magnet for releasing the locking device, and a single manually operated control element connected to said actuators for engaging the clutch and opening said valve and resetting the locking device.

4. A sheet feeder comprising an endless conveyor for transporting sheets to a machine to be fed, means provided with suction grips for lifting and transferring a top sheet from a pile to the conveyor, a main driving shaft, means for driving the conveyor from the driving shaft including a clutch, a conduit connected with said suction grips, a valve in said conduit, an actuator for engaging and disengaging said clutch, an actuator for said valve, means interconnecting the clutch and valve actuators, spring means urging the clutch to disengaged position and the valve to closed position, a locking device for retaining the clutch engaged and the valve open against the action of said spring, a sheet detector positioned at the end of said conveyor, means controlled by the sheet detector and operable for releasing the locking device, and a single manually operated control element connected to said actuators for engaging the clutch and opening said valve and resetting the locking device, a shaft carrying said manually actuated element, a segment on said last mentioned shaft, a lever having a portion movable into the path of travel of said segment for blocking movement thereof, an eccentric rotated in synchronism with the main-shaft and cooperating with said lever to periodically shift said lever into and out of the path of movement of said segment.

5. A sheet feeder comprising an endless conveyor for transporting sheets to a machine to be fed, means provided with suction grips for lifting and transferring a top sheet from a pile to the conveyor, a main driving shaft, means for driving the conveyor from the driving shaft including a clutch, a conduit connected with said suction grips, a valve in said conduit, an actuator for engaging and disengaging said clutch, an actuator

ator for said valve, means interconnecting the clutch and valve actuators, spring means urging the clutch to disengaged position and the valve to closed position, a locking device for retaining the clutch engaged and the valve open against the action of said spring, a sheet detector positioned at the end of said conveyor, means controlled by the sheet detector and operable for releasing the locking device, a single manually operated control element connected to said actuators for engaging the clutch and opening said valve and resetting the locking device, suction means for holding the sheets on the conveyor during stoppage of the latter, and means cooperating with said valve for energizing said last mentioned suction means upon stoppage.

6. A sheet feeder comprising an endless conveyor for transporting sheets to a machine to be fed, means provided with suction grips for lifting and transferring a top sheet from a pile to the conveyor, a main driving shaft, means for driving the conveyor from the driving shaft including a clutch, a conduit connected with said suction grips, a valve in said conduit, an actuator for engaging and disengaging said clutch, an actuator for said valve, means interconnecting the clutch and valve actuators, spring means urging the clutch to disengaged position and the valve to closed position, a locking device for retaining the clutch engaged and the valve open against the action of said spring, a sheet detector positioned at the end of said conveyor, means controlled by the sheet detector and operable for releasing the locking device, a single manually operated control element connected to said actuators for engaging the clutch and opening said

- valve and resetting the locking device, suction actuated means for pressing on the top of the pile of sheets, and means for energizing said last mentioned means upon release of said locking means.
- 5 7. A sheet feeder comprising an endless conveyor for transporting sheets to a machine to be fed, means provided with suction grips for lifting and transferring a top sheet from a pile to the conveyor, a main driving shaft, means for driving the conveyor from the driving shaft including a clutch, a conduit connected with said suction grips, a valve in said conduit, an actuator for engaging and disengaging said clutch, an actuator for said valve, means interconnecting the clutch and valve actuators, spring means urging the clutch to disengaged position and the valve to closed position, a locking device for retaining the clutch engaged and the valve open against the action of said spring, a sheet detector positioned at the end of said conveyor, means controlled by the sheet detector and operable for releasing the locking device, a single manually operated control element connected to said actuators for engaging the clutch and opening said valve and resetting the locking device, and a manually actuated valve for controlling operation of the suction means.
